MULTISTAGE COMPRESSOR

Harry A. Feldbush, Short Hills, N. J., assignor to
Worthington Pump and Machinery Corporation,
New York, N. Y., a corporation of Virginia

Application June 19, 1934, Serial No. 731,240

1 Claim. (Cl. 230—199)

This invention relates to air or gas compressors and more particularly to multi-stage compressors wherein two-stage pistons are connected in line for unitary movement.

5 An object of the present invention is to provide in a multi-stage compressor as specified a bleed-off space between the high stage and low stage cylinders of the compressors, with a suitable tight packing structure about the high stage piston to 10 prevent leakage from the high stage cylinder into the low stage cylinder.

Another object of the present invention is to provide a novel self-aligning connection between the low stage piston and the high stage piston for 15 permitting the maintaining of the pistons in alignment or for compensating for any misalignment between them.

With these and other objects in view as may appear from the accompanying specification, the 20 invention consists of various features of construction and combination of parts, which will be first described in connection with the accompanying drawing, showing multi-stage compressors of the preferred form, and the features forming the 25 invention will be specifically pointed out in the claim.

In the drawing:

Fig. 1 is a longitudinal section through the cylinder construction of a multi-stage compressor 30 constructed in accordance with the present invention.

Fig. 2 is a cross section taken on the line 2—2 of Fig. 1.

Fig. 3 is a cross section taken on the line 3—3 35 of Fig. 1.

Referring more particularly to the drawing, 1 indicates the low stage or low pressure cylinder of a multi-stage compressor. The low pressure piston 2 reciprocates in the low pressure cylinder 1, 40 and it is connected through the medium of the connecting rod 3 with any suitable operating mechanism (not shown). The cylinder 1 is fitted with any approved type of valves as indicated at 4 and operates, by the reciprocation of the piston 2 to compress any suitable air or gas in the first or low pressure stage of the multi-stage compressor. A high pressure cylinder 5 is also provided which is positioned in line with the low pressure cylinder 1 and is connected thereto 45 through the medium of the connection extension 6 formed on the high pressure cylinder 5 and the head 7 of the low pressure cylinder. The head 7 is at the head end of the low pressure cylinder. A piston or plunger 8 reciprocates in the low pressure cylinder 5 and it extends through the crank end of the low pressure cylinder and into the cylinder head 7 when it is in its retracted position. The piston 8 has an extension or connector 9 thereon, which is in effect a part of the plunger or piston, 50 being of the same diameter. However, if it is so

desired, any suitable type of connector may be employed in lieu of the section of the piston 8 as shown in the drawing. The extension of the piston 8 or connector 9 is connected by means of an aligning joint 10 with the low pressure piston 2 5 so as to compensate for any slight misalignment between the pistons 2 and 8.

The joint 10 comprises a flanged stem 11 which extends into the coupling 12 and is held therein against longitudinal movement by the clamping 10 nut 14 which engages against the flange 15 formed on the inner end of the stem 11. As clearly shown in Figs. 1 and 2 of the drawing, the bore of the nut 14 is larger in diameter than the stem 11 providing the clearance space 16 and also the bore 15 of the coupling 9 is larger than the diameter of the flange 15 which, together with the clearance 16, will permit relative lateral movement of the stem 11 and coupling 12 to compensate for any slight misalignment of the pistons 2 and 8. 20

The coupling or connecting extension 6 has a bleed-off space or chamber 20 formed therein into which any leakage, past the piston 8 from the high pressure cylinder 5, may pass. The bleed-off chamber 20 may be open to atmosphere 25 through suitable ports as indicated at 21 or these ports may be closed by suitable caps 22. If it is so desired the bleed-off chamber 20 may be connected by any suitable means (not shown) to any suitable place, without departing from the spirit 30 of the invention, since the invention comprises essentially the provision of the space or chamber 20 between the high and low pressure cylinders for receiving the leakage from the high pressure cylinder. As clearly shown in Fig. 1 of the drawing, 35 the piston 8, in its retracted position extends into and through the cylinder head 7. For the purpose of preventing any leakage from the chamber 20 into the low pressure cylinder 1, a packing structure 23 of any approved type is carried by 40 the cylinder head 7 and surrounds the piston 8 and its connector or extension 9.

It is to be understood that the high pressure cylinder 5 is provided with any approved type of intake and discharge valves. 45

It will be understood that the invention is not to be limited to the specific construction or arrangement of parts shown but that they may be widely modified within the invention defined by the claim. 50

What is claimed is:

In a multi-stage compressor, in combination, a low pressure cylinder, a high pressure cylinder connected in line to said low pressure cylinder, a low pressure piston, a high pressure piston, a 55 bleed-off chamber between said cylinders, and open to said high pressure cylinder to receive any leakage passing said high pressure piston.
